Patented Sept. 11, 1962

193,577

GASOLINE PUMP CASING

Bolling H. Sasnett, Jr., 692 Longwood Drive NW,
Atlanta, Ga.

Filed Dec. 5, 1960, Ser. No. 63,103

Term of patent 14 years

(Cl. D52—2)

Fig. 2

Fig. 3

Fig. 4

FIG. 1 is a perspective view showing the front and one side of a gasoline pump casing embodying my new design;

FIG. 2 is a rear elevational view thereof;

FIG. 3 is an elevational view of the side thereof opposite that shown in FIG. 1; and

FIG. 4 is a top plan view thereof.

The dominant features of the design reside in the portions shown in solid lines.

I claim:

The ornamental design for a gasoline pump casing, substantially as shown and described.
